Isaac Engel, of Boston, Mass:
Letters Patent, No. 788. Dated May 13th 1856.

The schedule referred to in these Letters Patent, and making part of the same.

To all persons to whom these presents shall come:

Be it known that I, Isaac Engel, of Boston, in the County of Suffolk, and State of Massachusetts, have invented or produced a new ornamental design for the leg of a Piano-forte, or other article of furniture to which the same may be applicable; and I do hereby declare that the same is fully described and represented in the following specification and the accompanying drawings of which

Figure 1, exhibits a top view of said leg, or in other words, of the cap A, thereof.

Figure 2, a side elevation of the leg.

Figure 3, a side view of the capital of the leg, showing its form, previous to its mouldings being carved as shown in Figure 2.

Figure 4, is an under-side view of said capital.

Figure 5, is a top view of the base.

Figure 6, a side view of the base previous to being carved as shown in Figure 2.

Figure 7, is a top view of the part B, of the capital.

Figure 8, is a top view of the part C, of the same.

Figure 9, a top view of the part C, of the base.

Ms. 788

Figure 10, a top view of the part H, of the base.

Figure 11, a side view of the shaft before it is caved.

Figure 12, a side view of the screw pin I, which is inserted down through the axis or middle part of the capitol and fastened therein and made to project therefrom as seen in Figure 2, the screw of said pin serving to attach said leg to an article of furniture.

Figure 13, is a view of the pin or holder of the castor I, placed in the foot or base.

From these drawings, it will readily be understood the forms to be given to the different members and their moldings. - I would however remark that the shaft has a tapering form, and is composed of spiral or helical legs D, E, F, arranged with respect to one another as shown in the drawings.

What I claim is the ornamental design of a Piano-forte leg as constructed, substantially as represented in the drawings and in manner as above described.

In testimony whereof, I have hereunto set my signature this 7th day of April A.D., 1856.
